E. G. LAMSON, OF WINDSOR, VERMONT.

Letters Patent No. 89,265, dated April 20, 1869

IMPROVED STONE-CHANNELLING MACHINE.

The Schedule referred to in these Letters Patent and making part of the same.

To all whom it may concern:

Be it known that I, E. G. LAMSON, of Windsor, in the county of Windsor, and in the State of Vermont, have invented certain new and useful Improvements in Stone-Channelling and Grooving Machines; and do hereby declare that the following is a full, clear, and exact description thereof, reference being had to the accompanying drawings, and to the letters of reference marked thereon, making a part of this specification.

My improvements relate to a number of devices and combination of devices, and constructing a channelling and grooving-machine, to cut marble, or other rock, in quarries where the dip, strata, or layers of marble, or other rock, stand at an angle of forty-five degrees, or varying from that either way.

In very many of the quarries the marble stands in layers, varying from perpendicular to horizontal, and up to the present time no machine has been able to do the work successfully, and great difficulty has been experienced in quarrying. A great loss of material, when blocks are taken out, has been the result, unless cut by hand, as it is necessary to follow the dip, or seams, that is, to cut grooves between the layers, because there is generally a great difference in the quality of the different layers, one may be very good, and the next to it be very bad.

My machine is intended to cut a perpendicular groove, or to cut at any desired angle, to follow the dip, or strata, and cut a channel at right angle with the layer, and thereby take out square blocks of the same kind of material.

The design of my machine is to set it upon a level track, or to set it on a track standing at any desired grade, and to be able to make the machine feed itself up and down any desired grade, to accommodate itself to the layers, or strata to be cut.

My invention, therefore, partly consists in constructing the feed-works in such a manner, and the track, that I am enabled to feed the machine up and down the grades, which can be accomplished in a great many different ways.

One device is to use the friction of the wheels upon a track, giving motion to the driving-axles by a worm-gear, or its equivalent.

Another device is a rack, with cogs attached to the track, or its equivalent, and a pinion, or a worm-gear playing into the rack, which pinion may be on the driving-axle, or a separate shaft, with rack standing perpendicular, and the feed-mechanism may operate to carry the machine up and down any desired grade, while the cutting-device is doing its work on both sides of the track, or on one side, or between the tracks, in which latter case the cross-pieces in the track are removed.

Another device is to have two tracks, standing at convenient distance from each other, on the rock to be cut, and have two machines, and let them be connected

by a wire cable, rope, or chain, so as to let the machines balance each other, so that when one is going up, the other will be coming down, and thereby cut four grooves at the same time, or a loaded car may be used to counterbalance.

And still another device to feed the machine up and down steep grades, is, by means of a chain and cog-wheel put on to the driving-axle, and the end of said chain attached to the track, or some stationary object, the links of the chain fitting on to the cogs. When the cog-wheel is turned by the feeding-mechanism, the machine will be fed up or down on a grade.

There are various ways and manners of attaching the chain, or winding the chain around a drum, or in grooves, and only attaching one end of the chain to the track, and the other to the feeding-mechanism of the machine. I shall use any of the well-known ways of attaching, for feeding by a chain, or its equivalent.

Another device is by means of a wire rope, or strap, one end of which is attached to the feeding-shaft, or its equivalent, and the other end to a weight, the rope passing over loose pulleys on the end of the track, or a stationary fixture, and then running up to the sides or top of the quarry, or its equivalent, whereby the weight acts as a counterbalance, and the machine is fed up and down steep grades.

Another very important part of my invention is the arrangement of hanging the steam-boiler on trunnions, placing the trunnions, or bearings in such a position, that the lower part will be the heaviest, which I call a pendulum-boiler, for the purpose of running up and down grades, and keep the water over or around the tubes in the boiler, to prevent damage by heat on the tubes.

I place a small steam-pump on the boiler, for the purpose of keeping the supply of water in the boiler.

The boiler may be hung in various ways, to keep it perpendicular when running up and down grades. It may be set on rockers, or, by means of an adjustable bed, to change the position of the boiler, to change it, by screw or lever, by hand when desired, instead of having it hung like a pendulum.

I shall not confine myself to any one way, but use any devices known.

A perpendicular or horizontal boiler may be used.

As I use a flexible pipe or rubber hose to convey the steam to the engines, the boiler or engines may change their positions without trouble.

Another arrangement of using the boiler is by setting the boiler, in many cases, at a distance from where the machine is to be worked, as it happens that in tunnels and in deep shafts the smoke and gas are troublesome, also, the getting of fuel and water to the boiler, and getting rid of the escape-steam.

By setting the boiler on the bank of the quarry, out of the way, it can be of sufficient size to run a number of machines, and one fireman can keep up steam, the

steam or compressed air carried down in pipes of rubber, or other flexible pipe.

Another great improvement is to provide the frame with small standards, to which I hang the steam-engine beds.

These beds are hung, at the bottom, on trunnions, or a shaft, the other end of engine-bed being attached to adjustable braces, so as to give any desired angle to the bed, at pleasure.

On this engine-bed I place an oscillating engine crank-shaft, with eccentric-rod and feeding-arms, and a crank with wrist-pin, to which pin is attached a flexible instrument, that carries a gang of cutters, said cutters being attached to a cutter-holder, which slides on or between standards, attached to the engine-bed.

This part of my invention thus consists in the arrangement of engine, feeding and cutting-mechanism, all on one bed, and hung on trunnions, or their equivalents to give any angle desired to the cutters.

In order to enable others skilled in the art to which my invention appertains, to make and use the same, I will now proceed to describe its construction and operation, referring to the annexed drawings, in which—

Figure 1 is a side elevation, showing two sets of cutters working outside the frame and track, perpendicularly.

Figure 2 is an end view, showing one set of cutters working perpendicularly, and the other set at an angle.

Figure 3 is a plan view, with the boiler and cutting-apparatus removed, showing the feed-mechanism and the device for holding the cutting-apparatus in place when the track is in an inclined position.

Figure 4 is a longitudinal vertical section of the device, by which either engine or set of cutters is made to operate its feeding-mechanism, to move the machine along the track.

Figure 5 is a transverse vertical section of the same device.

Figure 6 is a side view of the feeding-device and its connection.

Figure 7 is a side view of the arm and collar operating the feeding-device, so as to feed in either direction.

Figure 8 is a side view of the double-acting feeding-pawl, showing its operation to feed the machine.

Figure 9 is a side view, and

Figure 10, a plan view of the clutch which holds the segmental feeding-connection in place.

Figure 11 is a cross-section of the track; and

Figure 12 is a longitudinal vertical section of the track, showing the same in an inclined position, and the manner of balancing the machine by a weight attached to a chain.

Figure 13 is a plan view of a head-clamp with guide-rollers.

Figure 14 shows another construction of the flexible instrument.

A represents the track, which is secured to the rock in any position desired, and by any suitable means.

This track is provided with a rack-bar, B, in which cog-wheels on the driving-axles of the machine gear, so as to move the machine along in either direction.

C is the frame on which the whole machine is placed, said frame resting on wheels D D, placed on the ends of the shafts, or axles E E, and resting on the track A.

On one side of the frame C are four ears or small standards F F, the outer ends of which are one at each end of the frame, and the other two at suitable distance from the former, each set, of two standards, forming bearings for an engine-bed, G.

The engine-beds G G are, at their lower ends, on the inner side, provided with ears and bolts, passing through said ears, and through the standards F F, thus pivoting the engine-beds G G, at their lower ends, to the frame C.

On the inner side of the bed G is secured a frame,

H, which contains the engine, as will be hereinafter fully set forth.

At the upper rear end of the frame H is pivoted a screw-rod, I, which passes through an ear at the upper end of a bar, K, which is pivoted, at its lower end, to the opposite side of the frame C.

Nuts L L are placed on the screw I, one above and the other below said ear, so that the screw I and bar K form a brace for holding the engine-bed in position.

It will be seen that, by the use of the nuts L L, the upper end of the engine-bed can be raised and lowered at pleasure, thus placing said bed at any angle desired.

Inside of the frame H is hung an oscillating-engine cylinder, M, from which the piston-rod N communicates motion to the crank-shaft O, which has its bearings in the frame H.

The outer end of the crank-shaft O passes through the engine-bed G, and is, on the outer side of said bed, provided with a crank, P, which, by a pitman, Q, is connected with and operates the cutting-mechanism.

R R are the standard-guides, running parallel with the engine-bed G, and secured to the same at a suitable distance in front of it, by means of the supports S S, so that the crank P, pitman Q, and their connections, with the cutters, work between said bed and guides.

T T are the clamps, or cutter-holders, which carry the cutters V V, between the standard-guides.

It will be seen, that by the adjustment of the engine-beds G G, as above described, the cutters V V may be made to operate at any angle desired; also, that by the arrangement of two such beds, engines and set of cutters, as shown in the drawings, two seams may be cut at the same time, at different angles, or both may operate in the same channel.

On the crank-shaft O are placed the fly-wheel U and an eccentric, W, which latter, by a pitman, X, connects with a segmental arm, Y, pivoted on the same bolt, which pivots the engine-bed G to the frame C.

The segmental arm Y is cogged along its outer periphery, said cogs gearing into cogs on the outer periphery of a smaller segmental arm, Z, pivoted on a shaft, a, which has its bearings in the ends of the frame C.

The arm Z is placed by the side of a grooved wheel, b, secured on the shaft a, and on the other side of said wheel, on the shaft, is placed a bar, c. This bar and the arm Z are bolted together on each side of the grooved wheel b, so that they will move together loosely around the same.

The rear bolt connecting these two also passes through, and thus pivots the double-acting pawl d, the outer end of which is by the spring e connected with the end of the bar c, while the inner end is shaped so as to turn the wheel b and shaft a in either direction.

The outer end of the double-acting pawl d is, by a pin, connected with a two-armed lever, f, pivoted to the inner end of the segmental arm Z.

The arms of this lever are operated upon by a flange, or projection g, on a collar, h, placed loosely on the shaft a.

By moving this collar so that the flange g is in the centre, between the two arms of the lever f, it will be seen that the pawl d is held in such a position as not to touch the wheel b, and consequently will not turn the same, while, when said flange moves or bears against one of the arms, one side of the pawl will bear against the wheel, and turn it in one direction. When the flange g bears against the other arm, the motion is reversed.

The collar h is provided with an arm, i, which is connected by a rod, k, to an arm, m, on a shaft, n, which has its bearings in the frame C, and in a semicircular box, p, secured to the platform r, on which the boiler may rest.

The end of the shaft n , which has its bearing in the semicircular box p , projects a suitable distance within said box, and is provided, directly inside of the box, with a wheel, s , as seen in fig. 4.

Both of the engine-beds and sets of cutters being provided with such feeding-device as above described, the two shafts n project, one from each end, in the box p .

On the ends of the shafts n , inside of the box p , and between the wheels s , is placed a slotted block, t , through which a lever, v , passes, said lever being pivoted inside of said block, on a line with the ends of the shafts n , the lower end of the lever passing downward projecting below the block.

Through the block t , below and parallel with the shafts n , runs a bolt, w , through which the lever v also passes, so that by moving the lever to one end the bolt passes to the other, the end of the bolt projecting through the block t , and into a hole on the wheel s .

By now turning the lever to one side or the other, to nearly a horizontal position, the wheel s and shaft n are turned so as to throw the feeding-device connected with said shaft into gear.

By turning the lever v toward the other, the bolt w enters the other wheel, s , and consequently the other feeding-device will be thrown into gear, while when said lever stands in a vertical position, neither one of the feeding-devices is in gear.

It will thus be seen that by the use of this lever I can make the machine stand still, or either one of the feeding-devices move it either backward or forward at pleasure.

The shaft a is provided with worms x , which gear into cog-wheels y , on the axles E , and thus communicating the motion from the feeding-devices to the machine.

To obviate any danger of one of the shafts n turning when it is desired to turn the other, I provide the ends of the semicircular box p , on the outside, with other boxes, z , in which moves a bolt, a' , pressed inward by a spiral spring, v' , so that the inner ends of said bolts will project into the holes already mentioned on the wheels s .

When the bolt a is moved to either end, it will press the bolt a' out of the hole in the wheel s , and take its place so as to turn said wheel.

Across the centre of the bottom of the semicircular box p is a projecting flange, o , with a slot in its centre, so as to hold the lever in a vertical position, and also, when turned to either side, to prevent it from slipping out of its place.

On the platform r rests the boiler A' , which is, by means of flexible pipes, connected with the steam-boxes attached to the oscillating cylinders M , as shown in fig. 1.

I prefer, however, to attach standards B , B' to the sides of the platform r , and provide the boiler A' with trunnions C , inserted in the upper ends of said standards, so that the boiler can accommodate itself to any movement up or down a grade, or when one side of the track is higher than the other.

The pitman Q , which, as above described, contributes or communicates the necessary motion to the cutting-apparatus, is attached to a bow-spring, D , and this spring to the lower clamp, which holds the cutter.

By reason of the flexibility of the bow-spring D , the usual jar and concussion to the machinery are, if not entirely, at least to a considerable degree lessened, and consequently the danger of any injury to the machinery greatly obviated.

Another mode of constructing such a flexible mechanism I have represented in fig. 14.

It consists of a double pitman, made in two pieces, and attached to the crank P in the usual manner, and

letting them run down any length desired, and attached to the foot-clamp.

The lower ends of the two pitmen E , E' stand at any desired distance somewhat in the shape of a letter A , both the upper ends being connected or attached to the crank.

At about the middle of the two flexible arms or pitmen E , is a rod, e , passing through the same.

On or around this rod or shaft, I place a spiral spring, d , which keeps the lower ends of the two pitmen at any proper distance.

Instead of the spiral spring d , a number of springs, of a round or oval shape, with a hole in the middle, one side convex and the other concave, or any other kind of a spring, may be put between the two arms.

In this way I obtain a flexible or yielding mechanism similar to the bow-spring. Both are yielding and accumulative in their action, like the bow-spring, and perform the same function.

The segmental cogged arms y , which communicate motion to the feeding-mechanism, as above set forth, are movable on the shafts or bolts which pivot them.

A bisected clutch, F , shown in figs. 9 and 10, placed on said shaft or bolt, keeps the arm Y in proper position to perform its function.

In fig. 12, I have represented a portion of the track in an inclined position, showing the rack-bar B and the pinion y , gearing into the same.

On the shaft E , I then place a wheel, G , having a series of pins, e , at equal distances apart, on its outer periphery.

A chain, H , the links of which are of such size as to fit successively on the pins e , is passed around the wheel G , one end of said chain being attached to the track or some other stationary object, and the other end passing over a pulley, I , placed at any suitable point.

This end of the chain has a weight, J , attached to it, to counterbalance the weight of the machine.

Along the entire length of the rack-bar B , on both sides, is a projecting flange, i , and from the frame of the machine extend arms, having rollers m , m' at their lower ends, which rollers fit on the under side of the flange i , as shown in fig. 11, thus preventing any side or sliding motion of the machine.

I may also, for the purpose of feeding the machine up or down a grade, place a pulley, K , on the shaft E , and pass a wire cable, rope, or chain, L , around the same, both ends of said rope being secured to the ends of the track, as seen in fig. 3, and thus I am enabled to feed the machine along by merely turning the axle E without any rack and pinion.

In fig. 13, I have shown an improved head-clamp, which may be placed at any point desired on the standard-guides R , to suit the depth of the groove and size of the cutters.

On the inner side of said clamp are placed flanged rollers n , n' , between which the cutters or chisels V , V' move, the flanges on said rollers embracing the edge of the cutters, and guide it in its upward and downward movement.

The rollers n , n' may be made adjustable, so as to be made to suit one or more cutters, or any size of cutter.

Having thus fully described my invention, What I claim as new, and desire to secure by Letters Patent, is—

1. The arrangement, upon the bed-frame C , of the two sets of cutters V , V' , upon or around the guides R , arranged upon the same side of the frame, and at each side of a boiler, A' , to operate outside of the frame and track, either vertically or at an angle, and braced upon the rear of the bed-frame, substantially as set forth.

2. In a stone-grooving or channelling machine, the method herein described of moving the machine up and down steep grades, by means of a rope, chain, or their equivalents, substantially as set forth.
3. The arrangement of the toothed wheel G' , chain H' , and weight J' , with a stone-channelling and grooving machine, substantially as set forth.
4. A stone-channelling or grooving machine, which is mounted upon a frame supporting a horizontal or upright steam-boiler, which is hung on trunnions, whereby the same will retain its normal position, irrespective of the incline or angle of the bed-frame, substantially as set forth.
5. In a stone-channelling or grooving machine carrying two or more engines and two or more sets of cutters, an arrangement of devices by which either engine may be made to feed the machine in either direction along the track, substantially as herein set forth.
6. Connecting the feed-mechanism with an eccentric on the main shaft of the engine in such a manner that the said feed-mechanism shall be operated at whatever angle the engine, engine-bed, and cutting-apparatus, may be placed, substantially as herein set forth.
7. The cogged segmental arm Y , provided with a collar encircling the trunnion-shaft of the engine-bed G , and held in position by the clutch F' , substantially as and for the purposes herein set forth.
8. The combination, with the shaft a , of the worm-gear z , axle E , spur-wheel y' , and rack-bar B , whereby the spur-wheel is made to act upon its upper and lower face, substantially as set forth.

In testimony that I claim the foregoing, I have hereunto set my hand, this 2d day of April, 1869.

E. G. LAMSON.
